TIRE

John O. Antonson, Tallmadge, Ohio, assignor to The
B. F. Goodrich Company, New York, N.Y., a corpora-
tion of New York

Filed Dec. 27, 1965, Ser. No. 339

Term of patent 14 years

(Cl. D90—20)

FIG. 1

FIG. 2

FIG. 3

FIG. 1 is a perspective view of a tire showing the new design, it being understood that the tread portion is repeated throughout the circumference of the tire and that the shoulder design is repeated throughout the circumference of the shoulder, the opposite side of the tire being substantially like the side shown with the exception that the tire sidewall is black;

FIG. 2 is an enlarged fragmentary plan view of the tread portion of the tire shown in FIG. 1; and

FIG. 3 is a fragmentary transverse sectional view through the tire substantially on the plane indicated by the line 3-3 of FIG. 2.

I claim:

The ornamental design for a tire, substantially as shown and described.
